US00D980056S

(12) **United States Design Patent** (10) **Patent No.:** **US D980,056 S**
(45) **Date of Patent:** **** Mar. 7, 2023**

(54) **FASTENER FOR PACKAGING**

(71) Applicant: **AR Packaging Systems AB**, Lund (SE)

(72) Inventor: **Anna Naukkarinen**, Helsingborg (SE)

(73) Assignee: **GPI Systems AB**, Lund (SE)

(**) Term: **15 Years**

(21) Appl. No.: **29/737,225**

(22) Filed: **Jun. 7, 2020**

(30) **Foreign Application Priority Data**

Jun. 1, 2020 (EM) 007960885-0008

(51) **LOC (14) Cl.** **09-03**

(52) **U.S. Cl.**

USPC **D9/416**

(58) **Field of Classification Search**

USPC D24/130, 200, 206, 215, 188-192;
D29/100, 108, 120.1, 121.1, 121.2;
D30/146; D9/416, 434, 438, 449, 499,

D9/419

CPC .. B65D 1/02; B65D 1/06; B31B 50/81; B65B

7/2878
